United States Patent Office

Des. 224,802
Patented Sept. 19, 1972

224,802

CLOCK

Jack Gabel Conner, 6013 Tulip Hill Road,
Worthington, Ohio 43085

Filed May 5, 1971, Ser. No. 140,635

Term of patent 14 years

Int. Cl. D10—01

U.S. Cl. D42—7

Fig. 1

Fig. 2

FIG. 1 is a top plan view of a clock showing my new design;

FIG. 2 is a side elevational view thereof.

The model space capsule shown in approximately the eight o'clock position moves around the dial to indicate the time.

I claim:

The ornamental design for a clock as shown and described.
